ELECTRIC DISCHARGE-TUBE SYSTEM

Application filed January 7, 1925, Serial No. 1,072, and in the Netherlands February 9, 1924.

This invention relates to an installation for operating an electric discharge tube comprising an incandescent cathode, an anode, a controlling grid, and a so-called foregrid.

5 A "foregrid" is to be understood to mean an auxiliary electrode having some apertures and arranged between the cathode and the controlling grid; this foregrid must have a positive potential relative to the cathode and 10 has preferably about the same potential as the anode.

Besides the foregrid there may be provided one or more other auxiliary grids or auxiliary electrodes.

15 The invention has for its principal object to connect the installation for operating such a discharge tube so as to be suitable for generating, receiving, or amplifying electric oscillations without making use of a retroaction coil.

In the known retroaction circuit-arrangements, which for example are utilized in triodes, there are used for the connection of the anode-circuit to the grid-circuit two separate 25 coils wound in opposite directions or a single coil. In the latter case the anode and the grid are each connected to one of the ends of the said coil while the cathode is connected to an interjacent point of the coil.

30 It is not possible to arrange a single coil to belong to the grid circuit as well as to the anode circuit because the anode current fluctuations have the same phase as the tension or voltage variations at the grid (that is to say: The anode current increases as the grid 35 tension increases and vice versa).

In discharge tubes comprising a foregrid which has a positive potential relative to the cathode, preferably a potential corresponding to that of the anode, the anode current fluctuations are in a certain region in phase with the tension or voltage fluctuations at the grid. The foregrid current fluctuations are however in opposite phase therewith, 45 that is to say: If the tension of the controlling grid decreases the foregrid current increases, and conversely. The tensions at the anode and the foregrid are in this case supposed to be constant.

50 In the accompanying drawings, Figure 1

shows diagrammatically the construction of an installation, according to the invention, which is particularly suitable for amplifying oscillations of low frequency. Figure 2 shows the current-voltage characteristics of the circuit.

In Figure 2 of the accompanying drawing the foregrid current i_g and the anode current i_a are set out as a function of the controlling grid tension v_g ; while the anode- and the foregrid tension are kept constant in this case. It appears that in a given interval (between the points C and D) of the controlling grid-tension the anode current i_a decreases when the grid tension decreases, while in the same region the foregrid current i_g increases.

This property is utilized in order to obtain an installation comprising a circuit in which a negative resistance occurs.

For this purpose an ohmic resistance is provided which pertains to both the current circuits formed between the incandescent cathode and the controlling grid and between the incandescent cathode and the foregrid. In this case the foregrid has preferably substantially the same potential as the anode.

According to the invention one end of the resistance is electrically connected to the incandescent cathode whereas the other end is electrically connected to the foregrid and through a battery to the controlling grid.

The resistance is preferably non-inductive and is adjustable so that the voltage applied to the control grid and the foregrid may be varied. It is also advantageous to provide batteries for the anode and foregrid such that the potential applied by either or both to the respective electrodes may be varied.

With the aid of Figure 1 it is easy to see that a circuit can be indicated in which a negative resistance occurs.

The electric discharge tube shown in Figure 1 consists of an envelope 1 of glass or similar material, in which an incandescent cathode 2, a foregrid 3, a controlling grid 4, and an anode 5 are arranged.

The envelope 1 may be exhausted to a high degree or may contain a suitable gaseous filling at low pressure; it may for example be

filled with a rare gas, preferably with argon having a pressure of 100 microns or less.

The incandescent cathode 2 is heated to the required temperature by a battery 6 while the anode circuit is provided with a battery 11 and a telephone 12. The foregrid 3 is likewise connected to the battery 11 with the interposition of a regulable resistance 10 and the controlling grid 4 is connected to the resistance 10 via a secondary coil 8 of a transformer 8, 9 and a battery 7 having a tension which is equal to or a little higher than that of the battery 11.

It will be noticed that the resistance 10 pertains to the foregrid circuit as well as to the controlling grid circuit while the resistance is electrically connected to the incandescent cathode and to the two grids.

It has now been found that a current tension characteristic measured for example between the points P and Q of the opened grid-circuit has a dropping character so that the resistance between the points P and Q is a negative one. This may be seen from the following:

If at a constant tension or voltage of the controlling grid v_g the tension $v_{g'}$ of the foregrid is increased, the current $i_{g'}$ flowing towards the foregrid will increase; consequently:

$$\left(\frac{\delta i_{g'}}{\delta v_{g'}}\right)v_{g'} > 0$$

If on the contrary v_g is increased and $v_{g'}$ is kept constant, the current $i_{g'}$ flowing to the foregrid will decrease, for if the potential of the controlling grid becomes more positive, the anode current will increase, owing to which electrons which at a smaller tension v_g would move towards the foregrid are deflected to the anode. The anode takes therefore more current at the cost of the foregrid so that the current flowing to this grid decreases. Consequently:

$$\left(\frac{\delta i_{g'}}{\delta v_{g'}}\right)v_{g'} < 0$$

If P and Q are imagined to be electrically connected with the interposition of measuring instruments, the current i_g in this grid-circuit will be the total amount of i_g and $i_{g'}$. Also dI will be equal to the sum of di_g and $di_{g'}$.

As, however, the controlling grid has a potential which is slightly negative relatively to the cathode, there will occur substantially no currents towards the said grid and the change of this grid-current will therefore be negligible in practice. Consequently:

$$dI = di_g$$

Furthermore a tension fluctuation at the controlling grid will cause an equally great tension fluctuation at the foregrid and consequently, too, at the point P. To the tension

fluctuation dV_g at the point P there applies consequently:

$$dV_g = dv_g = dv_{g'},$$

$$dI_g = di_g = \frac{\delta i_{g'}}{\delta v_g} dv_g + \frac{\delta i_{g'}}{\delta v_{g'}} dv_{g'},$$

and consequently:

$$dI_g = \left(\frac{\delta i_{g'}}{\delta v_g} + \frac{\delta i_{g'}}{\delta v_{g'}} \right) dV_g,$$

In order that there be a negative resistance between the points P and Q it is necessary that

$$\frac{\delta i_{g'}}{\delta v_g} + \frac{\delta i_{g'}}{\delta v_{g'}} < 0$$

From the above deductions it appears that the first term of the left member of this inequality is negative; the second, on the contrary, is positive so that consequently the condition for a dropping characteristic is that in absolute value

$$\left(\frac{\delta i_{g'}}{\delta v_g} \right) > \left(\frac{\delta i_{g'}}{\delta v_{g'}} \right)$$

In general this condition is satisfied and there is consequently a negative resistance between the points P and Q.

The value of the resistance 10 is substantially equal to the absolute value of the negative resistance in the circuits which is common to the two grids so that the total resistance in this circuit approximates 0.

The installation according to the invention is plainer than the one usually used heretofore, because a retroaction coil has become useless; it may be applied to the generation, reception and amplification of oscillations, more particularly to the reception or amplification of oscillations of high or low frequency and offers in some cases the advantage of an easier adjustment than the usual retroaction circuit arrangements.

That the installation illustrated is very suitable for the amplification of oscillations of low frequency may appear from which follows:

If tension fluctuations occur at the primary coil 9 of the transformer they are transmitted to the secondary coil 8 so that consequently, for example, the tension at the grid 4 decreases a little. This decrease of the tension at the controlling grid, the tension of which is equal to or a little lower than that of the cathode 2, causes an increase of the current in the foregrid circuit (see Figure 2).

The loss of tension in the resistance 10 increases now and this causes a decrease of the tension of the two grids. As however the tension decrease at the controlling grid has a greater influence on the foregrid current than the tension fluctuation at the foregrid, (the latter is in phase with the foregrid current fluctuations and exerts therefore an influence

opposite to the one of the controlling grid) the foregrid current keeps increasing even now. This causes again a decrease of the tension of the grids and so on so that a tension fluctuation at the controlling grid after 5 being amplified is transmitted to the foregrid circuit. As the anode current decreases in about the same measure as the foregrid current increases (see Figure 2), the oscillations 10 of the controlling grid circuit are therefore also transmitted in an amplified manner to the anode circuit in which the telephone 12 has been put.

The amplifying is limited on account of the 15 total current which leaves the cathode, being able to rise only to a certain value, namely, to the saturation current.

By a proper choice of the value of the resistance 10 the amplification may be facilitated, for the resistance 10 is opposite to the negative resistance occurring in the foregrid circuit; and if the resistance 10, initially having a value smaller than the value of a negative resistance, is gradually increased the 25 line A—B in Figure 2 will become more and more inclined till, when the resistance 10 is equal to the negative resistance, the line A—B theoretically obtains a perpendicular position. In the latter case the changes of the 30 foregrid current are consequently in theory infinitely great with any fluctuation in the controlling grid.

The resistance 10 is preferably free of induction as otherwise the current fluctuations 35 in the foregrid circuit are not accurately in phase with the tension fluctuations at the controlling grid.

What I claim is:

1. A discharge tube relay having a cathode, 40 plate and two grids, a plate circuit comprising a source of positive plate potential, a foregrid circuit comprising said source of plate potential and a resistance, and a control grid circuit comprising said source of plate potential, said resistance, a source of negative potential, and an input means.

2. A discharge tube relay having a cathode, plate and two grids, a plate circuit comprising a source of positive plate potential, a foregrid circuit comprising a resistance and a source of potential substantially equal to that of the plate, and a control grid circuit comprising said source of foregrid potential, said resistance, a source of negative potential, and 55 an input means.

3. A discharge tube relay having a cathode, plate and two grids, a plate circuit comprising a source of positive plate potential, a foregrid circuit comprising said source of plate potential and an adjustable resistance, and a control grid circuit comprising said source of plate potential, said resistance, a source of negative potential, and an input means.

4. In a discharge tube relay having an 60 anode, cathode, two grids and a negative re-

sistance characteristic, a plate circuit comprising a source of positive plate potential, a foregrid circuit comprising said source of plate potential and an ohmic resistance substantially of the same value as the negative 70 resistance characteristic of the tube, and a control grid circuit comprising said source of plate potential, said resistance, a source of negative potential, and an input means.

In testimony whereof I affix my signature, 75 at the city of Eindhoven, this 15th day of December, A. D. 1924.
